United States Patent Office.

EDWIN M. SCOTT, OF AUBURN, NEW YORK.

Letters Patent No. 67,355, dated July 30, 1867.

IMPROVEMENT IN MACHINE FOR GRINDING REAPER-KNIVES.

The Schedule referred to in these Letters Patent and making part of the same.

TO ALL WHOM IT MAY CONCERN:

Be it known that I, E. M. Scott, of Auburn, in the State of New York, have invented certain new and useful Improvements in Machines for Grinding Reaper-Knives; and I do hereby declare that the following is a clear, full, and exact description of the same, reference being had to the annexed drawings, and to the letters of reference marked thereon, in which—

Figure 1 represents a side elevation.

Figure 2, a plan view of the swinging frame with clamps attached.

Figure 3, a view of the various parts which slide upon the table or bench.

Figure 4, a view of the toothed lever, by which the frame is held; and

Figure 5, a view of one leg of the bench and one end of the frame, showing the manner of hinging one to the other.

This invention has for its object the grinding of reaper-knives and giving them a uniform bevel, substantially in the manner hereinafter described; and to enable others skilled in the art to make and use it, I will now describe its construction and operation.

A represents a table or bench, to the legs of which is hinged the frame H, as fully shown in fig. 5. Said frame is provided with clamps I I I, for the purpose of holding the reaper-bar while the knives are being ground. This frame is also provided with holes g g g, in which the toothed lever k is placed to press the knives against the stone. B and B' are slides, one on top and the other beneath the horizontal bars of table A, as seen in fig. 1. The top slide B has a semicircular slot cut through it, as shown in fig. 6, the object of which will be fully seen hereafter. c represents a circular plate or disk, and is provided with the collar F; said collar should have two recesses cut in it, one side of each division being sloped, as partly seen in fig. 3. G represents a lever, and E a loose bolt, passing through said lever, disk C, collar F, and slides B B'. This bolt is secured at its lower end by means of a nut. It will thus be observed that by turning the lever G it will rise to the top of collar F, thereby drawing the slides B B' against the top bars of the bench A, and by this means securely retaining all of the sliding apparatus at any desired point. a represents a bolt which passes through the circular plate c, and also through the semicircular slot in slide B. Said bolt is provided with a thumb-screw, as seen in figs. 1 and 3. By the arrangement just described the grindstone can be set and fixed at any desired angle. h h are uprights, secured to the circular-plate c, (see fig. 1.) At the top of these uprights are the necessary journals, through which passes the shaft x. On one end of this shaft is secured the grindstone M, and at the other crank N.

In operating my machine I first secure the reaper-bar on frame H by means of clamps I I. I then slide the stone to the desired point, and turn lever G to secure it. I then place the stone at an angle corresponding to the bevel I wish the knives to be ground. The toothed lever k is now inserted in the holes just in front of the stone, by means of which the knives are held against the stone until sufficiently ground, when the slides may be loosened and again adjusted. Thus the operation continues until the whole work is performed.

What I claim, and desire to secure by Letters Patent, is—

1. In combination with disk C I claim slides B B' and thumb-screw d, as and for the purpose set forth.
2. I claim disk C; slides B B', loose-bolt E, lever G, all combined substantially as and for the purpose specified.

In testimony that I claim the foregoing I herewith affix my signature in presence of two witnesses.

EDWIN M. SCOTT.
